UNITED STATES PATENT OFFICE

132,275

DESIGN FOR A POSTER OR SIMILAR ARTICLE

Edward John Genter, New London, Conn.

Application February 18, 1942, Serial No. 105,882

Term of patent 7 years

To all whom it may concern:

Be it known that I, Edward John Genter, a citizen of the United States, residing at New London, in the county of New London and State of Connecticut, have invented a new, original, and ornamental Design for a Poster or Similar Article, of which the following is a specification, reference being had to the accompanying drawing, forming part thereof.

The figure is a plan view of a poster or similar article showing my new design.

I claim:

The ornamental design for a poster or similar article, as shown.

EDWARD JOHN GENTER.
